UNITED STATES PATENT OFFICE

106,373

DESIGN FOR A DRESS

Concetta Jaccarino, Brooklyn, N. Y.

Application July 26, 1937, Serial No. 70,655

Term of patent 3½ years

To all whom it may concern:

Be it known that I, Concetta Jaccarino, a citizen of the United States, residing at 1122 71st Street, in the Borough of Brooklyn, city and State of New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

The dress is crossed by a wool braid embroidery having loops and running horizontally across the dress in graduated lines.

I claim:

The ornamental design for a dress, substantially, as shown and described.

CONCETTA JACCARINO.
